UNITED STATES PATENT OFFICE.

PETER G. VAN WIE, OF DETROIT, MICHIGAN, ASSIGNOR TO THE IDEAL MANUFACTURING COMPANY, OF SAME PLACE.

DESIGN FOR A BROILER.

SPECIFICATION forming part of Design No. 32,755, dated May 29, 1900.

Application filed May 2, 1900. Serial No. 15,276. Term of patent 14 years.

To all whom it may concern:

Be it known that I, PETER G. VAN WIE, a citizen of the United States, residing at Detroit, in the county of Wayne and State of Michigan, have invented and produced a certain new and original Design for Broilers, of which the following is a specification, reference being had therein to the accompanying drawings, in which—

10 Figure 1 is a perspective view, and Fig. 2 is a side elevation.

A is a casing, which in general form is substantially rectangular. The greater portion of the front is formed by a rectangular door 15 B, which has a raised panel C, and at its side the rearwardly-extending flanges D, forming complementary portions of the sides E of the casing. Between the flanges D and sides E is formed a well-defined division-line having 20 an upper inclined portion *a*, a lower oppositely-inclined portion *b*, and a connecting

portion *c*. The sides E are provided with downward extensions F, inclining downward from front to rear.

The leading feature of the design is the substantially-rectangular casing having the door forming the greater portion of the front and the complementary sides of the casing and rearwardly-projecting side flanges on the door forming between a division-line having upper and lower oppositely-inclined portions and a central connecting portion. 25

What I claim as my invention is—

20 The design for a broiler, substantially as herein shown and described. 35

In testimony whereof I affix my signature in presence of two witnesses.

PETER G. VAN WIE.
